UNITED STATES PATENT OFFICE.

ALFRED E. JOHNSON, OF DENVER, COLORADO.

CARTRIDGE-FUSE.

1,266,599.

Specification of Letters Patent. Patented May 21, 1918.

Application filed December 20, 1915. Serial No. 67,763.

To all whom it may concern:

Be it known that I, ALFRED E. JOHNSON, a citizen of the United States, residing at the city and county of Denver and State 5 of Colorado, have invented certain new and useful Improvements in Cartridge-Fuses; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention relates to improvements in cartridge fuses, and one of my objects is to provide a device of this character simple and compact in construction, and one in which the fuse can be readily and quickly 20 replaced without the aid of tools.

Another object of my invention is to divide the interior of the cartridge into two compartments by means of a partition, and to locate a spiral spring in one of said compartments and connect a fuse therewith in such a manner that when an excess or over-load of current is introduced the break in the fuse can take place in one compartment only, and the moment the said break occurs, 25 the portion of the fuse connected with the said spring will instantly be drawn into the other compartment, whereby the arc formed between the broken extremities of the fuse will be quickly broken and the flame extinguished.

30 Still another object of my invention is to form a frustum-shaped connection between several convolutions of the spiral spring and one extremity of the fuse, whereby the 35 closest possible contact is formed between the said elements.

Having briefly outlined my improved construction, I will proceed to describe the same in detail, reference being made to the accompanying drawing, in which is illustrated 40 an embodiment thereof. In this drawing,—

Figure 1 is a view of one of my improved cartridge fuses completely assembled.

Fig. 2 is an end view taken in the direction of the arrow 2, Fig. 1.

Fig. 3 is a similar view showing the cap open for the insertion of the fuse.

Fig. 4 is an end view taken in the direction of the arrow 4, Fig. 1, showing one extremity of the fuse secured in position.

Fig. 5 is a similar view with the fuse pro-

truding beyond one extremity of the cartridge but unattached thereto.

Fig. 6 is a longitudinal view of the cartridge fuse taken on the line 6—6, Fig. 1, 60 looking in the direction of the arrow.

Fig. 7 is a similar view showing the relation of the parts after the fuse is melted.

Fig. 8 is a similar section showing the fuse inserted in the cartridge but before it is 65 secured under tension.

Fig. 9 is a detail view of the fuse which I employ.

The same reference characters indicate the 70 same parts in all the views.

Let the numeral 5 designate a cylindrical shell or casing open at its extremities and composed of rubber, fiber or other non-conducting material. Metallic caps 6 and 7 are respectively fitted over the opposite extremities of the shell, and are detachably connected therewith by means of bayonet joints 8. The cap 6 has a relatively large opening 4 while the cap 7 is provided with a smaller opening 9. A plate 10 is pivotally mounted at 11 upon the cap 6 adjacent the opening therethrough, and is adapted to cover or uncover said opening as circumstances require.

The shell 5 is provided interiorly with a 85 partition 12 also composed of suitable insulating material, and which partition divides the interior of the said shell into two compartments 13 and 14, the compartment 13 being slightly larger than the compartment 90 14. This partition 12 has a frustum-shaped opening 15 therethrough, for a purpose hereinafter described.

A spiral conducting spring 16 is attached at one extremity to the cap 6 at 17, and 95 wound cylindrical in shape adjacent this extremity as shown at 18, while its inner extremity is free and wound frustum-shaped as disclosed at 19. A fuse wire 20 is adapted to be inserted into the shell through the 100 opening 4 in the cap 6, said fuse wire passing through the frustum-shaped opening 15 in the partition 12 and the opening 9 in the cap 7, whereby it will project beyond the opposite extremity of the said shell as shown 105 at 21. One extremity of this fuse is formed frustum-shaped as disclosed at 22, and, therefore, will be retained within the spring 16, the surface of the frustum-shaped portion of said fuse closely engaging the convolutions of the spring 16 forming the 110 frustum-shaped extremity 19. By virtue of

the corresponding shape of the extremities of the fuse wire and the spring when the latter is distended, the closest possible contact will be formed between the two elements, which is absolutely necessary in order for the cartridge to efficiently perform its function. The portion of the fuse directly adjacent the frustum-shaped extremity 22 is slightly enlarged as shown at 23, while the remainder of the fuse may be of any lesser size.

Assuming that the elements are now assembled as disclosed upon Fig. 8 of the drawing, the extremity 21 of the fuse is 15 grasped and pulled outwardly whereby the spring 16 is distended or expanded until its inner or frustum-shaped extremity engages the partition 12 which will permit the enlarged portion 23 of the fuse to pass 29 through the opening 15 in the said partition and project slightly into the compartment 14, after which the extremity 21 of the fuse is wound around the pins or buttons 24, secured exteriorly to the cap 7 (see Fig. 4). 25 The cartridge is then ready for use as disclosed in Figs. 1 and 6, and its metal capped extremities are inserted into contact clips (not shown) in the usual manner, whereby the current will pass from one pair of said 30 clips through the cap 6, the spring 16, the fuse 20, the pins or buttons 24, and the cap 7 to the other contact clips, thereby completing the circuit.

If the current is increased to such an extent that it will melt the fuse, the break will 35 occur in the compartment 14 and forward of the enlarged portion 23 of the fuse, since naturally the smaller portion of the latter will melt first, and the instant the said fuse 40 is broken the spring 16 will be released and jerk the portion of the fuse connected therewith through the opening 15 in the partition 12 and into the compartment 13, whereby the arc formed between the extremities of the 45 fuse will be quickly broken and prevented from reforming by virtue of the intervening partition.

The cap 6 is then detached from the shell, whereby the end of the fuse connected with 50 the spring can easily be removed by pushing it through the spring and the opening in the cap 6.

In order to detach the other portion of the fuse it is only necessary to unwind it 55 from the pins or buttons 24 when it can be readily withdrawn through the opening 9 in the cap 7. The cap 6 is then again applied to the shell and a new fuse substituted by inserting the same through the opening 4 60 in the cap 6 as heretofore explained.

Attention is called to the fact that the pivotally mounted plate 10 at all times covers the opening 4 through the cap 6 except when a new fuse is being substituted 65 for a broken one.

From the foregoing description it will be readily understood that a broken fuse can be removed from the cartridge and a new fuse substituted without the employment of any tools whatever.

Having thus described my invention, what I claim is:—

1. A cartridge fuse comprising a casing, a partition located within said casing and provided with an opening, metallic perforated caps detachably applied to the opposite extremities of said casing, a spiral spring also located in the casing and having one extremity connected with one of said caps, a fuse having one end formed frustum-shaped 75 adapted to be inserted through the perforated cap adjacent said spring to enter the large end of the spring and provided with an end portion adapted to engage the opposite end of the spring which is also formed 80 frustum-shaped, whereby a close contact is formed, the said fuse extending through the opening in the partition and the perforation in the other cap, and means mounted upon the last named cap and around which 85 the other end of the fuse is adapted to be wound.

2. A cartridge fuse comprising a cylindrical casing, a partition located within said casing and provided with an opening, perforated metallic caps detachably applied to the opposite extremities of said casing, a spiral spring secured at one extremity to one 95 of said caps and its opposite extremity being wound frustum-shaped, a fuse one end of 100 which is secured within the frustum-shaped extremity of the spring, said end of the fuse being also formed frustum-shaped to conform to the interior of said spring, the said fuse extending through the opening in the 105 partition and the perforation in the other cap, and means mounted upon the last named cap to which the other end of the fuse is adapted to be attached.

3. A cartridge fuse comprising a casing, 110 electrical contacts removably provided at the extremities of said casing, a frustum-shaped coiled spring within said casing, and connected to one end thereof, the end of the casing having the spring attached thereto 115 being provided with an opening, and a removable fuse adapted to be inserted in said opening and enter the large end of said frustum-shaped spring, said fuse having a conical end part co-operating with the small 120 end of said spring to form a close contact therewith and means for securing the opposite end of said fuse to the opposite end of the casing.

4. A cartridge fuse comprising a casing, 125 perforated caps removably secured to its extremities, a coiled frustum-shaped spring attached to one of said caps within the casing and a removable fuse member adapted to be inserted through the perforated end cap ad- 130

jacent said spring, to enter the large portion of said spring, said fuse having an end portion engaging the small end of said spring and means for securing said fuse at 5 the opposite end of the casing.

5. A fuse comprising a casing, an open partition located in the latter and dividing it into two compartments, metallic caps provided with openings and detachably applied 10 to the opposite extremities of said casing, a spring located in one of said compartments and secured to one of said caps, a fuse attached to said spring and having an enlarged portion adjacent said connection, said fuse 15 extending through both compartments, the

opening in the other cap and beyond the latter, whereby the spring may be distended until it engages the partition and said enlarged portion of the fuse projects slightly into the other compartment, and means 20 mounted exteriorly upon the last named cap to which the fuse is also adapted to be attached for holding the spring and fuse in their operative positions.

In testimony whereof I affix my signature, 25 in presence of two witnesses.

ALFRED E. JOHNSON.
